COMBINED TELEPHONE STAND AND SEAT

Richard M. Phillips, East Peoria, Ill.

Application June 2, 1954, Serial No. 30,785

Term of patent 14 years

(Cl. D15—1)

FIG. 1.

To all whom it may concern:

Be it known that I, Richard M. Phillips, a citizen of the United States and a resident of East Peoria, county of Tazewell, State of Illinois, have invented a new, original, and ornamental Design for a Combined Telephone Stand and Seat, of which the following is a specification, reference being had to the accompanying drawing, forming a part hereof.

Fig. 1 is a front perspective view of a combined telephone stand and seat embodying my new design; and Fig. 2 is a rear perspective view of the same.

I claim:

The ornamental design for a combined telephone stand and seat, as shown.
